UNITED STATES PATENT OFFICE.

WILLIAM F. PRICE, OF READING, PENNSYLVANIA.

DESIGN FOR A VAPOR-BURNER DEVICE.

SPECIFICATION forming part of Design No. 31,246, dated July 18, 1899.

Application filed June 23, 1899. Serial No. 721,643. Term of patent 7 years.

To all whom it may concern:

Be it known that I, WILLIAM F. PRICE, a citizen of the United States of America, and a resident of Reading, in the county of Berks 5 and State of Pennsylvania, have invented a certain new and original Design for a Vapor-Burner Device, of which the following is a specification.

My invention relates particularly to the incandescent type of vapor-burners; and it consists in a new and original form of supply and vaporizing device therefor, as shown in the accompanying drawing, the essential features of which comprise a body *a*, having an 10 inlet *b*, a doubled and bent vaporizing-tube *c*,

rising therefrom, and a depending vapor passage-way *d e*, terminating in a vertical discharge-valve chamber *f*, with burner-tip *f'*, all adapted for application to an ordinary Welsbach-mantle mechanism.
